(57) **CLAIM**

The ornamental design for a plastic bottle, as shown and described.

DESCRIPTION

FIG. 1 is a front elevation view of a first embodiment of a plastic bottle;

FIG. 2 is a rear elevation view of the first embodiment of a plastic bottle;

FIG. 3 is a left side elevation view of the first embodiment of a plastic bottle;

FIG. 4 is a right side elevation view of the first embodiment of a plastic bottle;

FIG. 5 is a top plan view of the first embodiment of a plastic bottle;

FIG. 6 is a bottom plan view of the first embodiment of a plastic bottle;

FIG. 7 is a front elevation view of a second embodiment of a plastic bottle;

FIG. 8 is a rear elevation view of the second embodiment of a plastic bottle;

FIG. 9 is a left side elevation view of the second embodiment of a plastic bottle;

FIG. 10 is a right side elevation view of the second embodiment of a plastic bottle;

FIG. 11 is a top plan view of the second embodiment of a plastic bottle; and,

FIG. 12 is a bottom plan view of the second embodiment of a plastic bottle.

The broken lines in the drawings showing the plastic bottle illustrate the portions of the plastic bottle that form no part of the claimed design.

1 Claim, 8 Drawing Sheets
